UNITED STATES PATENT OFFICE.

EVERETT E. WARNER, OF HARTFORD, CONNECTICUT.

WING FOR FLYING-MACHINES.

No. 881,836.

Specification of Letters Patent. Patented March 10, 1908.

Application filed June 22, 1907. Serial No. 380,269.

To all whom it may concern:

Be it known that I, EVERETT E. WARNER, citizen of the United States, residing at Hartford, in the county of Hartford and State of Connecticut, have invented certain new and useful Improvements in a Wing for Flying-Machines, of which the following is a specification.

The object of my invention is to provide a device of the class specified which has features of novelty and advantage.

Figure 1 is a plan view of my wing. Fig. 2 is a cross section on line XX of Fig. 1. Fig. 3 is perspective view of the wings on a machine.

The frame-work of the machine would necessarily be of very light material preferably of aluminium tubing. Any size and form of construction could be used, the one in the drawing being merely to show how the wing is set up. In an actual machine the frame work would be much lighter and smaller relatively to the wings than that shown in this figure.

Referring to the drawing: A is the frame of a wing which is adapted to be arranged on both sides of a flying-machine. There may be a multiplicity of these wings on either side of the machine provided they balance one another. Through the center of said frame and running longitudinally with the machine is an axis B of the wing. This axis is suitably secured to the machine proper by the braces C so that the wing is free to oscillate.

I prefer that the oscillation on the axis B shall not exceed 90 degrees. That is, that while the outside of the frame sweeps down 90 degrees, the inside sweeps up 90 degrees correspondingly. Consequently, both the outside and the inside of the wing oscillate 45 degrees above and below the horizontal plane. The oscillation itself is provided by any well known means such as gearing connected to some power device.

Transversely arranged on the frame A and connected with axis B are wires D D arranged in pairs. Secured to each pair of wires and extending backward underneath the next pair of wires, are flaps F F made of suitable

light flexible material. Feathers might be used for flaps.

When the air pressure is from below, that pressure closes the flaps; so that we have a flat surface resisting the air. When the air pressure is from above, that pressure opens the flaps and sends the machine ahead. As a means for preventing the flaps from rising above the plane of the wing when the air pressure is from below I prefer to use the transverse wires. The flaps on the outside of the axis are separate from those on the inside of the axis because when the wing oscillates the flaps on each side alternate in opening according to the air pressure. When the pressure is from above, the flaps open part way, being prevented from opening to the full extent by the fact that each flap is fastened at its front end to a pair of wires. Consequently as the air forces its way downward through these openings, the flaps act as a series of cams and the air striking them on the slant forces the machine ahead.

The advantage of a wing of this kind is that when placed, one or more, on each side of the machine, they give it steadiness, raise it and drive it forward without the aid of any balloon or other means of raising or propelling the same.

The chief essential in a flying-machine is lightness and this is secured by the elimination of all other means of propelling and also by the fact that by merely oscillating instead of revolving, the flaps open and close automatically thus being free from the necessity of having some heavy mechanism such as would be used to regulate the opening and closing of the flaps if the wings revolved. Also if the machinery should fail to work, the flaps would close automatically thus preventing a rapid fall.

By oscillating my wing, the outside presses down, makes a flat surface against the air, and raises the machine; while correspondingly the inside of my wing rises and the downward air pressure forces the machine ahead. When the wing oscillates back, the flaps on the inside force the machine up, while those on the outside force it ahead.

Claims.

1. In a flying-machine, a wing adapted to oscillate on an axis longitudinal with the machine, transverse wires secured to said axis, and flaps secured at their front ends to said transverse wires in separate series on each side of said axis.
2. In a flying-machine, a wing adapted to oscillate on an axis longitudinal with the ma-

chine, pairs of transverse wires secured to 10 said axis, and flaps secured at their front ends to each pair of said wires.

In testimony whereof I affix my signature in presence of two witnesses.

EVERETT E. WARNER.
